UNITED STATES PATENT OFFICE.

GEORGE E. SMITH, OF EXETER, NEW HAMPSHIRE.

TROLLEY.

SPECIFICATION forming part of Letters Patent No. 728,313, dated May 19, 1903.

Application filed April 5, 1902. Serial No. 101,512. (No model.)

To all whom it may concern:

Be it known that I, GEORGE E. SMITH, a citizen of the United States of America, and a resident of Exeter, in the county of Rockingham 5 and State of New Hampshire, have invented certain new and useful Improvements in Trolleys, of which the following is a specification.

This invention relates to an improvement 10 in trolleys for electric-car service.

The object of the invention is to simplify and perfect the construction of the trolley and improve it in many respects and enable it, more particularly, to hold the wire firmly 15 without losing its grip thereon.

It consists, essentially, in a hinged or auxiliary spring-actuated frame carrying a supplemental or second wheel designed to engage 20 the conductor and to remain in engagement with the latter when the main wheel or truck ceases to contact with said conductor; and the invention consists, moreover, in numerous details and peculiarities of the construction and combination, as will be herein- 25 after set forth.

In the annexed drawings, illustrating my invention, Figure 1 is a front elevation of my improved trolley. Fig. 2 is a side view.

Similar numerals of reference denote like 30 parts throughout both figures.

1 denotes the trolley-pole. To the upper end of this is fastened, by means of suitable pins or otherwise, the yoke or harp 2, having the parallel forks 3 3, in the upper ends of 35 which is supported the truck journal or shaft 5, carrying the main truck 4, which revolves between the forks 3 3. The shaft 5 projects horizontally a short distance beyond the forks 3 3 in both directions. On these projecting ends are supported the lower ends of 40 the parallel arms 13 13 of the auxiliary frame, in which is carried the horizontal shaft, stud, or journal 16, on which is the supplemental truck or wheel 15. The upper ends of the 45 parallel arms 13 are made integral with the flaring inclined arms 14 14, that so project upwardly as to afford abundant room between them to catch the wire or conductor and surely and accurately guide it to the upper truck, notwithstanding wide deflections 50 and oscillations in the movement of the pole. On the ends of the journal 16 are nuts 17 for

holding the journal firmly in its bearings. Between the arms 13 and the hub of the truck 15 are the antirattling-springs 18 18. 55 Between the forks 3 3 and the hub of the truck 4 are similar antirattling-springs 12 12. With the arrangement above described the trolley has much better opportunity to catch the wire, for there is much more abundant 60 space between the arms 14 14 wherein the wire or conductor can be caught than is the case with the forms of trolley in common use. Inside of each truck 4 and 15 is a suitable bushing, which can easily be renewed when worn 65 out.

On the shorter of the two projecting ends of the journal 5, that end having the nut 6, is supported the oscillating arm 13. On the other or longer of the projecting ends of the 70 same journal 5 is a coiled spring 8, one end of which engages a slot or notch in the journal, while the other end projects upwardly and bears against a lug or ear 11 on the side of the adjacent arm 13. The object of this 75 spring is to lift the arms 13 13 and upper wheel 15 whenever the main wheel 4 starts to leave the wire. In the same end of the journal 5 that carries the spring 8 is a screw 7 for the purpose of firmly attaching the upper end of 80 the guide 9 thereto, the lower end of this guide being secured to the yoke or harp 2 by means of a bolt or screw 10. Guide 9 consists of an angular strip of metal made fast, as stated, to yoke 2 and journal 5 and serving 85 to prevent the spring 8 from catching or engaging with the wires or conductors.

In the drawings the upper truck 15 is shown in its elevated or lifted position, which it will occupy whenever the main wheel 4 has been 90 disengaged from the wire, and at the same time the arms 13 and the projecting arms 14 are in their uppermost position. If now these arms 14 embrace or receive the wire, it will first go to the upper truck and after the 95 same has been touched and pressed upon the pressure of the trolley-pole will cause the said upper truck to be closed down, together with the arms, allowing the wire to reach the main truck 4, so that both trucks will run on the 100 wire. When the arms are thus closed down, everything will be below the center of the wires and switches, so that there will be nothing projecting to engage improperly

therewith. On the side of the yoke or harp 2 is a projection 21 to limit the downward movement of the upper-wheel-carrying frame and prevent it from dropping too low when 5 depressed. In the operation of the trolley whenever the main truck leaves the wire the upper and smaller truck 14 will be lifted up and held against the wire to prevent it from being lost.

10 Having thus described my invention, what I claim as new, and desire to secure by Letters Patent, is—

15 1. In a trolley, the combination with the main yoke, a journal therein, a main wheel on the journal, a second or auxiliary wheel, a journal therefor, a frame supporting said journal, which frame has widely-diverging arms to catch the wire, and a spring coiled about and attached to the journal of the main 20 wheel, and having one end engaging the frame of the second wheel.

2. In a trolley, the combination with the

main yoke and its wheel, of the auxiliary wheel and its frame, a spring engaging the journal of the main wheel and also the 25 frame of the second wheel, and a guide for preventing said spring from becoming entangled with the wires, said guide being secured to the main yoke.

3. In a trolley, the combination with the 30 main yoke and its wheel, of the auxiliary wheel and its frame, a spring engaging the journal of the main wheel and connected to the frame of the auxiliary wheel, and a guide for preventing said spring from becoming entangled with wires, said guide being made fast to the journal of the main wheel and also to the main yoke.

Signed at Exeter, New Hampshire, this 28th day of March, 1902.

GEORGE E. SMITH.
